UNITED STATES PATENT OFFICE

157,571

WIRE BASKET

E. Lucian Dennis, Rockford, Ill., assignor to The Washburn Company, Worcester, Mass., a corporation of Massachusetts

Application August 20, 1949, Serial No. 4,619

Term of patent 14 years

(Cl. D58—4)

To all whom it may concern:

Be it known that I, E. Lucian Dennis, a citizen of the United States, residing at Rockford, in the county of Winnebago and State of Illinois, have invented a new, original, and ornamental Design for a Wire Basket, of which the following is a specification, reference being had to the accompanying drawing, forming part thereof.

In the drawing:

Fig. 1 is a plan view of a wire basket, showing my new design;

Fig. 2 is a front view of Fig. 1.

I claim:

The ornamental design for a wire basket, as shown.

E. LUCIAN DENNIS.
